UNITED STATES PATENT OFFICE.

PHILIP A. MYERS, OF ASHLAND, OHIO, ASSIGNOR TO F. E. MYERS AND BROTHER, OF ASHLAND, OHIO, A COPARTNERSHIP COMPOSED OF FRANCIS E. MYERS AND PHILIP A. MYERS.

DESIGN FOR A PUMP-CASING.

• 57,371.

Specification for Design.

Patented Mar. 15, 1921.

Application filed November 17, 1919. Serial No. 338,771. Term of patent 14 years.

To all whom it may concern:

Be it known that I, PHILIP A. MYERS, a citizen of the United States, residing at Ashland, in the county of Ashland and State of Ohio, have invented a new, original, and ornamental Design for a Pump - Casing, of which the following is a specification, reference being had to the accompanying drawings, forming part thereof.

Figure 1 is a side elevation illustrating a pump of my improved design;

Fig. 2 is a detail end view of a pump illustrated in Fig. 1.

I claim:—

The ornamental design for a pump casing as shown.

PHILIP A. MYERS.
